UNITED STATES PATENT OFFICE.

DAVID C. BLAKE, OF DURHAM, NORTH CAROLINA.

SCREEN DOOR AND WINDOW CONSTRUCTION.

1,351,940.

Specification of Letters Patent.

Patented Sept. 7, 1920.

Application filed April 12, 1920. Serial No. 373,217.

To all whom it may concern:

- Be it known that I, DAVID C. BLAKE, a citizen of the United States, residing at Durham, in the county of Durham and State 5 of North Carolina, have invented certain new and useful Improvements in Screen Door and Window Construction, of which the following is a specification, reference being had to the accompanying drawings.
- 10 This invention relates to screen door and window construction and has for its object to provide an improved method or construction of this character capable of being used for both windows and screen doors, and 15 wherein the screen fabric is not only secured at its edges to the frame, but is also clamped to the frame adjacent its edges so that it is impossible for the same to accidentally disengage itself from the frame and 20 in fact, will resist any effort to force the screen from the frame unless the screen is removed in the proper manner.

Another object is to provide a construction of this character including a frame 25 composed of two sections secured to each other, the joints of the sections being disposed in angular relation with respect to each other to brace said joints.

Another object is to provide means for 30 securing the wire fabric to one section, said means also serving as a tenon for connecting the parts of said sections to each other.

Another object is to provide a construction 35 of this character which eliminates the forming of mortise and tenon joints in the meeting ends of the parts of the frame, so as to strengthen the frame.

With these and other objects in view the invention consists in the improved construction 40 and arrangement of parts to be herein-after more particularly described, fully claimed and illustrated in the accompanying drawings, in which:

Figure 1 is a vertical elevation view of a 45 screen closure constructed in accordance with an embodiment of the invention, a portion of one of the sections being cut away to show the inner face of the adjacent section;

50 Fig. 2 is a section taken on the line 2—2 of Fig. 1;

Fig. 3 is a vertical elevation of the joint of one of the sections of the closure.

Referring to drawings, 5 designates a 55 closure constructed in the form of a window

screen or door and is composed of two sections 6 and 7.

The section 6 includes top and bottom members 8 and side members 9. As the construction of the joints of each side member 60 and each top and bottom member are similar, the description of one will suffice for all.

Each of the side members 9 has the end portions of its inner marginal edges reduced as at 10 to provide a canted shoulder 65 11. It will be noted that the inner marginal edges of the members 8 and 9 are beaded or provided with various designs of molding. The adjacent member 8 has the corner 12 of its end portion canted. The end portion 13 70 of the member 8 is intended to engage the reduced portion 10 of the member 9 while the canted corner 12 engages the canted shoulder 11.

This construction permits the molding to 75 be mitered in the usual fashion without requiring the end portions of said members to be mitered.

Each of the members 8 and 9 are provided with longitudinally extending grooves 13, 80 which are positioned centrally of said members in one face thereof. The reduced end portions of the member 9 is provided with laterally extending mortise grooves 14 which intersect the grooves 13 of the members 8 85 and extend through the sides of the reduced end portions.

In view of the mortise groove, the groove 13 of the members 8 and 9 are permitted to intersect each other. Screen fabric 15 is 90 extended over the section 6 and has its marginal edges disposed in the grooves 13 and in a portion of the mortise groove 14. A securing key 16 is disposed in each of the grooves 13 of the members 9 and is intended to secure said fabric in the grooves. 95

A securing key 17 is disposed in each of the grooves 13 of the members 8. The end portions of the key 17 extends beyond the ends 13 of the members 8 to provide tenons 100 18 adapted to be received in the mortise grooves 14. The tenons 18 extend laterally of the reduced portion of the members 9 and not only serve to hold the corners of the screen fabric in engagement with the section 105 6 but also assist in connecting the members 8 and 9 to each other without requiring the formation of mortise and tenon joints in said members which would greatly weaken the structure. To further assist in strength- 110

ening the members 8 and 9 a bracket 19 is secured to the members 8 and 9 and extends over the mitered joints of the canted shoulder 11 and corner 12.

5 The section 7 includes top and bottom members 20 and side members 21, the end portions of each of the members 20 and 21 being mitered for engagement with each other. The members of section 7 are intended to be disposed over the surface of the section 6 having the keys 16 and 17 and secured thereto. This clamps the portion of wire fabric extending over the inner marginal edge of the section 6 between said sections, so that additional securing means is thereby provided. Furthermore, the engagement of the end portions 13 of the members 8 and reduced portions 10 of the members 9 form a straight joint, while the mitered ends of the members 20 and 21 form angular joints and serve to strengthen each other. The mitered end portions of the members 20 extend over the joints of the members 8 and 9 to assist in further securing the members of section 6 to each other. Securing means such as screws, may be used for fastening the members 20 and 21 to the members 8 and 9.

From the foregoing it will be readily seen that this invention provides a novel and substantial form of construction for closures, which permits screen doors to be made in various styles, that is, including panels and other forms of design, as the structure is firmly braced and will last indefinitely. It can also be used in the construction of screen windows, closures for sky-lights, and in fact any form of screen closure desired. An important feature of this invention is that the wire fabric is so firmly secured that it affords security not possible with the old method of securing screen fabric to a frame as it is not only fastened in the grooves of

the section 6 by the keys 16 and 17, but is also clamped between the members, and will therefore resist any force to pry the fabric from the sections. In fact the fabric itself will be broken or mutilated by the force before the marginal edges thereof will be separated from the section 6 so that it is impossible for a person to force the hand between the screen fabric and the sections to unfasten the closure without mutilating the screen fabric.

What is claimed is:

A screen closure comprising two sections adapted to engage each other, each section including top, bottom and side members, each of the members of one section having a longitudinal groove in one face thereof, the end portions of said side members having a laterally extending mortise groove intersecting the end portions of the longitudinal groove, the end portions of the top and bottom members of said section engaging the side portions of the side members, screen fabric extending over said sections and having its ends disposed in the groove, key members disposed in said grooves for holding the screen fabric therein, the end portions of the key of the top and bottom members extending beyond the ends of said members to provide tenons, said tenons being disposed in the mortise grooves of the side members, the top and bottom side members of the other section having their ends mitered and engaged with each other, the end portions of the top and bottom members of the second mentioned section extending over the adjacent joints and tenons of the first mentioned section, and means for securing said sections to each other.

In testimony whereof I hereunto affix my signature.

DAVID C. BLAKE.
